DESIGN FOR A LADY'S BOUDOIR SLIPPER OR SIMILAR ARTICLE

John L. Jerro, Brooklyn, N. Y.

Application February 6, 1936, Serial No. 60,995

Term of patent 3½ years

To all whom it may concern:

Be it known that I, John L. Jerro, a citizen of the United States, residing in the Borough of Brooklyn, county of Kings, city of New York, and State of New York, whose post-office address is 40 West 27th Street, Borough of Manhattan, county of New York, city of New York, and State of New York, have invented a new, original, and ornamental Design for a Lady's Boudoir Slipper or Similar Article, of which the following is a specification, reference being had to the accompanying drawing, forming a part thereof.

The characteristic feature of the design consists of a high elongated vamp extending into a point over the instep of the wearer, the outer edges of the vamp curving from the point over the instep rearwardly towards the point adjacent the forward edge of the heel.

I claim:

The ornamental design for a lady's boudoir slipper or similar article, as shown and described.

In testimony whereof I have signed this specification.

JOHN L. JERRO.
